US0D1084872S

(12) United States Design Patent (10) Patent No.: US D1,084,872 S
(45) Date of Patent: * Jul. 22, 2025

(54) COSMETIC BOTTLE

(71) Applicant: The Procter & Gamble Company,
Cincinnati, OH (US)

(72) Inventors: U-Ping Loh, Singapore (SG); Yun Qin Lee, Singapore (SG); Caroline Colin, Singapore (SG)

(73) Assignee: The Procter & Gamble Company,
Cincinnati, OH (US)

() Term: 15 Years

(21) Appl. No.: 29/911,505

(22) Filed: Sep. 5, 2023

(51) LOC (15) Cl. 09-01

(52) U.S. Cl.

USPC D9/551; D9/558

(58) Field of Classification Search

(57) CLAIM

The ornamental design for a cosmetic bottle as shown and described.

DESCRIPTION

FIG. 1 is a perspective view of a cosmetic bottle;

FIG. 2 is a front view thereof;

FIG. 3 is a first side view thereof;

FIG. 4 is a back view thereof;

FIG. 5 is a second side view;

FIG. 6 is a top view; and,

FIG. 7 is a bottom view.

The broken lines illustrate structure or features that form no part of the claimed design.

1 Claim, 6 Drawing Sheets
